UNITED STATES PATENT OFFICE.

ANDREW D. HULQUIST, OF CHICAGO, ILLINOIS, ASSIGNOR TO J. S. McDONALD, OF CHICAGO, ILLINOIS.

LOCK FOR THE ADJUSTABLE BACKS OF LOOSE-LEAFED LEDGERS, ACCOUNT-BOOKS, RECORD-BOOKS, FILES, &c.

SPECIFICATION forming part of Letters Patent No. 749,992, dated January 19, 1904.

Application filed June 8, 1903. Serial No. 160,402. (No model.)

To all whom it may concern:

Be it known that I, ANDREW D. HULQUIST, a citizen of the United States, and a resident of Chicago, in the county of Cook and State of Illinois, have invented certain new and useful Improvements in Locks for the Adjustable Backs of Loose-Leafed Ledgers, Account-Books, Record-Books, Files, &c., of which the following is a full, clear, and exact description.

The object of my invention is to provide a simple and economical form of lock for the backs of loose-leafed ledgers, account-books, record-books, files, &c., the particular feature of which is that the bolt thereof is stationary and the elements of the lock are automatic in their action, according as it is desired to lock or unlock the same by resting the book on one side or the other and compressing the same. This I accomplished by the means hereinafter fully described and as particularly pointed out in the claims.

In the drawings, Figure 1 is a perspective view of the lock detached from the clamping-plates of the back of the book. Fig. 2 is a longitudinal central section through the same and the clamping-plates to which the parts thereof are attached, showing the same locked. Fig. 3 is a similar view showing the position of the parts of the lock when the book is reversed and the same unlocked. Fig. 4 is a longitudinal central section of the lock detached from the clamping-plates and illustrating a modified construction of the bolt.

Referring to the drawings, A and B represent the clamping-plates of the back of the book, to which the covers A' and B' are flexibly connected in any suitable manner. Secured rigidly to the clamping-plate A in any suitable manner is a bolt C, which projects at right angles therefrom toward the opposing clamping-plate B and is preferably cylindrical throughout its entire length. Near the unsecured end of this bolt the sides thereof are provided with elongated pockets a, which are preferably arranged or disposed oblique to the axis of the bolt. These pockets are preferably shallowest near the adjacent ex-

tremity of the bolt and gradually increase in depth as they extend therefrom. There may be one or more of these pockets a, and each is provided with a loose ball b, of steel or other suitable material, which is free to move in said pocket.

Rigidly secured to the clamping-plate B is a tube D, which projects at right angles therefrom toward plate A in such position that the bolt C enters the same and is in alinement therewith. The inner circumference of this tube is preferably provided with circumferential grooves d, which for convenience of manufacture are made spiral. Now when plate A is uppermost the gravity of the ball b causes it to move to the lower limit of the pocket a and by wedging itself between the bolt and the grooved inner circumference of the tube effectually locks and prevents the further separation of the tube and bolt. When the plate B, to which the tube D is secured, is uppermost, the gravity of the ball causes it to move into the deepest end of the pocket farthest from the adjacent extremity of the bolt, in which position the ball will be out of contact with the inner grooved circumference of the tube, and thus permit the free separation of the tube and bolt.

In Fig. 4 of the drawings I show a slightly modified construction of the bolt E and the tube F. In this modification the bolt is secured in any suitable manner to the clamping-plate A, and the tube is rigidly secured to the clamping-plate B in any suitable manner. The bore or inner wall f of the tube is corrugated or grooved in a manner similar to tube D of the lock hereinbefore described, and the edges g of the unsecured end are flanged inward, so as to restrict the diameter of the opening through which the barrel of the bolt E passes, substantially as shown.

The unsecured end of the bolt E within the tube F is near its extremity reduced in diameter to form a conical-shaped head G the truncated apex of which is integral to the end of the bolt and the base of which slightly exceeds in diameter that of the restricted opening in the unsecured end of the tube. I also employ in con-

junction with the head of this modified form of bolt a ball h , of steel or other suitable material, which is capable of movement in every direction. This ball h is placed between said head G 5 and the bore or inner wall of the tube F , which latter only slightly exceeds the diameter of the base of the flange of the head. Thus when the plate A , to which the bolt is secured, is uppermost ball h will gravitate down the inclined 10 sides of the conical-shaped head G and entering one of said corrugations will lock the bolt E , so as to prevent the further separation of the bolt and tube and the clamping-plates to which they are attached. When the plate B 15 is uppermost and said clamping-plates are pressed together to release the ball h , it will gravitate toward the apex of the conical sides of the head and in this position will be unable to lock or interfere with the free separation 20 of the tube and the bolt, which will only be limited by the base of the head G coming in contact with the flanged edges g of the end of the tube F .

It is obvious that the principal parts of my 25 invention, as hereinbefore described, may be changed or modified in construction without departing from the spirit of my invention. All such modifications not involving a departure from the principle of the lock, as 30 hereinbefore described, I desire to be understood as contemplating within the scope of my invention.

The covers A' and B' may, if desired, be dispensed with and the lock, with the clamping- 35 plates, be used for other purposes than clamping the removable leaves of books, ledgers, &c.

What I claim as new, and desire to secure by Letters Patent, is—

1. A lock comprising clamping-plates; a 40 bolt rigidly secured to and projecting from one of said plates; a tube secured to the other plate into which said bolt enters, the surface of the inner wall of which is uneven; and an independent gravity-controlled device interposed 45 between said bolt and tube for automatically locking the same together when in one position and unlocking them when in the reverse position.

2. A lock comprising clamping-plates; a 50 bolt rigidly secured to and projecting from one of said plates and provided with a longitudinally-disposed pocket in its unsecured end; a tube secured to the other plate into which said bolt enters, the surface of the inner wall 55 of which is uneven; and an independent gravity-controlled ball seated in said pocket for automatically locking the tube and bolt together when in one position and unlocking them when in the reverse position.

3. A lock comprising clamping-plates; a 60 bolt rigidly secured to and projecting from one of said plates and provided with a longitudinally-disposed pocket in its unsecured end which increases in depth as it extends from the 65 adjacent extremity of said bolt; and a tube se-

cured to the other plate into which said bolt enters, the surface of the inner wall of which is uneven; and an independent gravity-controlled ball seated in said pocket for automatically locking the tube and bolt together when in one position and unlocking them when in the reverse position. 70

4. A lock comprising clamping-plates; a 75 bolt rigidly secured to and projecting from one of said plates and provided with a longitudinally-disposed pocket in its unsecured end arranged oblique to the axis of said bolt; a tube secured to the other plate into which said bolt enters, the surface of the inner wall of which is uneven; and an independent gravity-controlled ball seated in said pocket for automatically locking the tube and bolt together 80 when in one position and unlocking them when in the reverse position.

5. A lock comprising clamping-plates; a 85 bolt rigidly secured to and projecting from one of said plates and provided with a longitudinally-disposed pocket in its unsecured end arranged oblique to the axis of said bolt and increasing in depth as it extends from the adjacent extremity of said bolt; a tube secured to the other plate into which said bolt enters, the surface of the inner wall of which is uneven; and an independent gravity-controlled ball seated in said pocket for automatically 90 locking the tube and bolt together when in one position and unlocking them when in the reverse position.

6. A lock comprising clamping-plates; a 95 bolt rigidly secured to and projecting from one of said plates; a tube secured to the other plate into which said bolt enters, the surface of the inner wall of which is circumferentially 100 grooved; and an independent gravity-controlled device interposed between said bolt and tube for automatically locking the same 105 together when in one position and unlocking them when in the reverse position.

7. A lock comprising clamping-plates; a 110 bolt rigidly secured to and projecting from one of said plates; a tube secured to the other plate into which said bolt enters, the surface of the inner wall of which is provided with a spiral groove; and an independent gravity-controlled device interposed between said bolt 115 and tube for automatically locking the same together when in one position and unlocking them when in the reverse position.

8. A lock comprising clamping-plates; a 120 bolt rigidly secured to and projecting from one of said plates and provided with a longitudinally-disposed pocket in its unsecured end; a tube secured to the other plate into which said bolt enters, the surface of the inner wall of which is provided with a spiral groove; and an independent gravity-controlled ball seated in said pocket for automatically locking the tube and bolt together 125 when in one position and unlocking them when in the reverse position. 130

9. A lock comprising clamping-plates; a bolt rigidly secured to and projecting from one of said plates and provided with a longitudinally-disposed pocket in its unsecured end 5 which increases in depth as it extends from the adjacent extremity of said bolt; a tube secured to the other plate into which said bolt enters, the surface of the inner wall of which is provided with a spiral groove; and an independent gravity-controlled ball seated in said pocket for automatically locking the tube and bolt together when in one position and unlocking them when in the reverse position.

10. A lock comprising clamping-plates; a bolt rigidly secured to and projecting from one of said plates and provided with a longitudinally-disposed pocket in its unsecured end arranged oblique to the axis of said bolt; a tube secured to the other plate into which said bolt enters, the surface of the inner wall of which is provided with a spiral groove; and an independent gravity-controlled ball seated in said pocket for automatically locking the tube and bolt together when in one position and unlocking them when in the reverse position. 15

tube and bolt together when in one position and unlocking them when in the reverse position. 25

11. A lock comprising clamping-plates; a bolt rigidly secured to and projecting from one of said plates and provided with a longitudinally-disposed pocket in its unsecured end 30 arranged oblique to the axis of said bolt and increasing in depth as it extends from the adjacent extremity to said bolt; a tube secured to the other plate into which said bolt enters, the surface of the inner wall of which is provided with a spiral groove; and an independent gravity - controlled ball seated in said pocket for automatically locking the tube and bolt together when in one position and unlocking them when in the reverse position. 35 40

In testimony whereof I have hereunto set my hand this 11th day of May, 1903.
